HONING TOOL

Kirke W. Connor and Albert Bleasdale, Detroit,
Mich., assignors to Micromatic Hone Corporation,
a corporation of Michigan

Application July 15, 1932, Serial No. 622,688

4 Claims. (Cl. 51—184.2)

Our invention relates to honing tools and particularly to a honing tool of the rigid type which is retained in rigid extension of the driving spindle.

5 The trend of the art in cylinder grinding and honing has been toward tools which may be operated at high speed to not only reduce the time of the grinding operation but also provide a better and finer finish on the wall of the cylinder. 10 When the speed of the conventional tool was increased, considerable difficulty was experienced because of the whipping of the tool relative to the cylinder wall which required the tool to be stopped before it was removed from the cylinder to prevent the abrading elements thereof from striking 15 the side wall and destroying its finish.

In practicing this invention we provide a tool which is employed primarily for high speed operation and which is so constructed as to permit the tool to be removed from the cylinder wall during its high speed operation without there being any danger of the abrading elements of the tool or other portions thereof striking the cylinder wall to mar the finish thereof. A rigid spindle is employed on the tool having a connecting portion which is engaged by the driving spindle of the machine in such manner as to form a rigid connection therewith to have the tool retained in fixed extended relation to the spindle. The rigid spindle of the tool prevents the whipping of the grinding end of the cylinder and the abrasive elements from contacting with the side of the cylinder wall when in contracted position.

To permit the abrading elements to adjust 35 themselves relative to the unalignment of the rigid spindle of the tool with the cylinder bore, we provide clearance between the conical expanding element of the tool and the spindle to permit the abrasive elements to center themselves relative to the bore, irrespective of the off-center 40 relation of the spindle thereto. The tool is provided with a guide plate on its lower end to protect the abrasive elements from striking the top of the cylinder block when the tool is inserted 45 into the bore thereof and springs are utilized for retaining the abrasive elements retracted against their seats adjacent to the spindle. The springs are employed at the top and bottom ends of the abrasive elements and are provided of different 50 strength. The spring at the top of the elements is of less strength than the spring employed in the bottom thereof to have the upper end of the abrasive elements move outwardly in case the conical adjusting element of the tool is inadvertently moved, to thereby permit the lower end

of the elements to enter the cylinder and to have the elements thereafter moved into parallel aligned relation as the movement into the cylinder progresses. This is made possible by employing a point contact between the abrasive element holders and the adjusting element to permit the tilting of the holders relative thereto which is also necessary to permit the complete universal adjustment of the holders relative to the unaligned spindle. 5

Accordingly, the main objects of our invention are; to provide a honing tool with a solid spindle which permits the tool to be operated at a high speed; to provide an adjusting element for the abrasive stones which moves the stones laterally 15 of the spindle and which permits the stones to center themselves relative to a cylinder bore irrespective of a slight off-center relation of the spindle thereto; to provide springs of relative strength, in the nature of garter springs, for retaining the abrasive stones in retrieved position in their seat; to mount the spring of greater strength at the lower end of the abrasive elements which will be retained in retrieved position when pressure is applied to the expanding elements 20 during the time the hone is inserted into a cylinder; to provide a guide plate at the end of the tool which prevents the abrasive element from striking the top of the cylinder wall; and, in general, to provide a honing tool which may be operated at high speed to rapidly machine the wall 25 of a cylinder and to produce an exceedingly high finish thereto. 30

Other objects and features of novelty of my invention will be either specifically pointed out 35 or will become apparent when referring, for a better understanding of our invention, to the following description in conjunction with the accompanying drawing, wherein:

Figure 1 is a view, partly in section and partly 40 in elevation, of a honing tool embodying features of my invention, and

Fig. 2 is a sectional view of the structure illustrated in Fig. 1, taken on line 2—2 thereof.

Referring to the figures, the honing tool 5 comprises a solid spindle 6 supporting an adjustable mechanism 7, a pressure exerting device 8 and a cutting head 9 all of which are revolvable with the spindle 6 and movable longitudinally thereof. The upper end of the spindle is rigidly secured 50 to a retaining and connecting head 11 through the medium of engaging threads and a cylindrical portion 12 in extension of the spindle which snugly engages a supporting and driving shank 13 to have the spindle mounted in rigid extension 55

thereof. A pin 14 extends through the portion 12 in engagement with slots in the shank 13 for supporting the two elements against relative longitudinal movement.

5 The adjustable head 1 comprises a cam carrying collar 15, a non-rotatable cam carrying member 16 mated therewith, and an adjustable nut 17 which regulates the amount of lateral extension effected to the abrading head 9 by the camming surface when moved relative to each other. The nut 17 is screwed upon a threaded extension 18 of a spring enclosing housing 19 which is retained against rotation relative to the spindle 6 by a pin 21 which projects within a slot 22 provided longitudinally of the spindle.

15 The cam collar 15 is retained relative to the member 11 on the spindle 6 against downward displacement by a washer 23. The upward bias of the collar 15, effected through the spring enclosing housing 19, the nut 17 and the member 16, is applied to a plurality of ball bearings 24, positioned between the upper surface of the collar 15 and the lower surface of the head 11. The ball bearings 24 reduce the frictional engagement 20 between the two members and permit the ready adjustment of the members 15 for a purpose which will be explained hereinafter. The cam carrying washer 16 is provided with a tongue 25 which projects within the slot 22 to prevent the 25 washer from rotating. A plurality of recesses or notches 26 are provided on both sides of the element 16 to effect a locking engagement with spring biased plungers 27 provided in the members 15 and 17 which are locked in predetermined 30 position thereby.

35 The member 17 is provided with a plurality of camming surfaces 28, which as illustrated in Fig. 1 are normally in nested relation with a plurality of camming surfaces 29 provided on the member 16. When the adjustable collar 15 is rotated 40 about the spindle 6 relative to the washer 16 the camming surfaces 28 and 29 pass upon each other to effect a downward thrust to the member 16 and therefore to the elements in engagement therewith. These elements include the adjustable nuts 17 and the spring enclosing housing 19 which, when moved downwardly apply a bias to a spring 31 supported within a cage 32 which is positioned about the spindle 6. The spring herein 45 illustrated is of preferred construction and is described and claimed in the copending application of F. M. Kern, Serial No. 521,092, filed March 9, 1931, and assigned to the assignee of the present invention.

50 The cage 32 limits the expansion of the spring and therefore permits the abrading elements of the head 9 to be moved a predetermined amount, after which the spring stress will be ineffective because of the complete expansion of the spring 55 within the cage 32. A washer 33 is mounted within the housing 19 above the spring cage 32 having an annular downwardly extending flange which projects over the cage in position to engage the spring 31 to apply a predetermined compression 60 thereto. A spring 34 is provided about the spindle 6, resting on a shoulder 35 thereof, for biasing the washer 33 upwardly out of engagement with the spring 31 when the camming elements 28 and 29 are in nested relation as illustrated in the 65 figure.

70 Below the spring cage 32 and in intimate contact therewith is provided an annular washer 36 having extending fingers 37 thereon which are guided in slots 38 in the sides of the spindle 6 75 to prevent the fingers from rotating relative to

the spindle 6. In this construction, the downward movement of the washer 33 stresses the spring 31 which applies a pressure through the cage 32 and the washer 36 to the fingers 37 to move them downwardly relative to the spindle 6. 5

A camming member 41, of frusto conical shape, is positioned about the lower portion of the spindle 6 for movement longitudinally thereof effected by the thrust applied to the fingers 37. Above and below the camming member 41, spiders 42 10 and 43 are secured in fixed relation to the spindle 6 by keys 44 and 45.

As illustrated in Fig. 2 the spiders are provided with a plurality of slots 46 for receiving the shoes 47 which support the abrading elements 48. The 15 abrading elements are of a form similar to that described in the co-pending application of G. M. Calvert, Serial No. 574,381, filed November 11, 1931, and assigned to the assignee of the present application and will not be further described. 20 The shoes 47 are provided with cam engaging surfaces 49 by which the abrading elements are adjusted laterally of the spindle 6 when the camming member 41 is moved longitudinally thereby. A spring 51 is provided below the camming member 41 in abutting relation to the spider 43 for moving the member 41 and fingers 37 upwardly when the camming collar 15 is moved to a position illustrated in the drawing. The camming surfaces 49 are of different slope from that 25 of the camming member 41 which effects a point contact therebetween to permit each shoe 47 to be 30 tiltable relative to the member 41.

35 The supporting members 52 of the abrading elements 48 are provided with arcuate ends 53 for receiving garter springs 54 and 55 which have the abrading element toward the spindle. The garter spring 54, positioned at the bottom of the tool, is of greater strength than the spring 55 positioned on the upper end of the abrasive elements. 40 When the adjusting nut 17 and the housing 19 are moved downwardly against the bias of the spring 51, the camming member 41 is moved downwardly to cause the abrading elements to be moved radially of the spindle. In the present 45 construction, because of the greater tension in the spring 54 than in the spring 55, the upper ends of the abrading elements 48 will be moved outwardly while the lower ends will be retained in substantially their collapsed position. The 50 purpose of this construction is to prevent the lower end of the head 9 from being expanded when the tool is inserted within a cylinder bore when the adjustable portion of the mechanism 55 has been moved downwardly.

55 As a further precaution in preventing the abrading element from striking the top of the cylinder housing when being inserted in a bore thereof, we provide a guiding member 56 which is secured to the end of the tool by a nut 57. The 60 guiding member is of a diameter substantial to that of the area encompassed by the abrading elements to thereby prevent the elements from striking against the top of the cylinder housing when the honing tool is being inserted within the 65 bore.

65 Referring again to Fig. 1, it will be noted that the camming member 41 has a greater internal diameter than the diameter of the spindle 6 for the purpose of permitting the lateral movement 70 of the camming member relative to the spindle, an amount sufficient to permit the centering of the abrading element 48 in a cylinder bore, irrespective of a slight off center position of the rigid spindle 6 therewith.

The operation of our tool will now be described. The tool is first assembled on the shank 13 through the insertion of the projection 12 in the recess thereof and turned to have the pin 14 supported within the slots communicating with the shank recess. The cylindrical extension 12 fits snugly within the recess to have the tool positioned as a rigid extension of the spindle. The nut 17 is then adjusted to effect the proper maximum expansion of the abrading elements 48 which will occur when the camming member 15 has been turned to have the cam 28 ride upon the cam 29. The camming nut 15 is then turned to collapsed position, which is that illustrated in Fig. 1, and the shank 13 is lowered to have the abrading elements enter the bore.

The camming member 15 is again operated to have the surface 28 ride upon the surface 29 to expand the abrading elements 48 against the bore 20 to be machined through the downward thrust applied to the adjusting nut 17 and the housing 19, after which the spring 31 is compressed. The honing tool is then rotated and the abrading elements machine the walls of the cylinder bore. 25 During the machining operation, the bias of the spring 31 effects a downward thrust to the fingers 37 and the camming member 41, to force the abrading elements 48 outwardly of the spindle 6. The expansion of the elements 48 continues until 30 such time as the spring 31 has expanded against the flanges of the spring cage 32 after which no further downward movement of the camming member 41 obtains and the lateral movement of the abrasive elements ceases.

35 During the operation of the tool at a time when the spindle 6 is in offset relation to the cylinder bore, the clearance between the camming member 41 and the spindle 6 and the ability of the holders 47 to tilt relative to the member 41 permits the abrasive elements 48 to center themselves at all times relative to the cylinder bore, to effect the correct machining of the bore irrespective of the off-center rotation of the spindle 6 therewith. After the machining operation, the rotation of the 45 honing tool may be stopped and the camming member 15 turned to the collapsed position, illustrated in Fig. 1, and the tool withdrawn from within the cylinder bore.

By having garter springs of different tension at 50 the ends of the abrading elements, we prevent the accidental expansion of the bottom portion of the abrading elements when the adjustable portion of the tool is moved downwardly, to prevent the ends of the abrading element from striking against the top of the cylinder block. In like manner the guide plate 56 prevents the striking of the abrading elements against the top of the cylinder block when the tool is inserted within the cylinder bore, the plate being provided with 55 sloping sides 58 for aiding in guiding the tool therewithin.

While we have described a tool of the manually adjustable type as being provided with the rigid spindle 6, it is to be understood that the 60 same principles embodied therein may be applied to a full automatic tool in which the expansion and the collapse of the honing elements occurs automatically when the tool is raised or lowered relative to its cylinder bore. Such an automatic 65 tool is illustrated and described in the co-pending

application of F. M. Kern, Ser. No. 521,089, filed March 9, 1931, and assigned to the assignee of the present invention. It is to be understood that the rigid spindle may be employed with the automatic head provided on the tool described in the above mentioned application and may be continuously rotated. When inserted within the bore the honing elements 48 will be in a collapsed position and after penetrating the bore a predetermined distance will be automatically expanded to have the elements moved into contiguous relation to the side of the cylinder bore. After the honing operation the upward movement of the tool collapses the element before they protrude a predetermined distance from the cylinder 15 bore, to thereby prevent the marring of the finish of the bore or damage to the abrading elements. In any application, the abrading elements have an opportunity to adjust themselves relative to the spindle both by tilting about the camming member 41 and by effecting the centering of the camming member relative to the spindle which may be slightly off center relative to the center of the cylinder bore.

While we have described and illustrated but a single embodiment of our invention it will be apparent to those skilled in the art that various changes, omissions, additions and substitutions may be made therein without departing from the spirit and scope of our invention, as set forth in the accompanying claims.

We claim as our invention:

1. A honing tool including, in combination, a unit spindle, expansible abrading elements tiltably mounted for radial movement on said spindle, a spring associated with the lower ends of said elements for biasing them inwardly toward the spindle, and a spring of less tension than said first spring associated with the upper ends of said elements for biasing them toward the spindle. 40

2. A honing tool including, in combination, a unit spindle, expansible abrading elements mounted on said spindle, a spring associated with the lower ends of said elements for biasing them inwardly toward the spindle, a spring of less tension than said first spring associated with the upper ends of said elements for biasing them inwardly about the spindle, and a guide plate at the end of said spindle of substantially the diameter of said elements. 50

3. A honing tool including, in combination, a unit spindle, expansible abrading elements mounted on said spindle, a spring associated with the lower ends of said elements for biasing them inwardly toward the spindle, and a spring of less tension than said first spring associated with the upper ends of said elements for biasing them inwardly about the spindle, and a guide plate having sloping side walls and secured to the end of the spindle for guiding the end of the tool into a cylinder to be bored. 55

4. A honing tool including, in combination, a driving member, an abrading head supported by said driving member, means for expanding said abrading head, and means for causing one end of said head to expand before the other when the head is unconfined and expanded. 65
